UNITED STATES PATENT OFFICE.

HENRY K. ADAMS, OF NASHVILLE, TENNESSEE.

APPARATUS FOR MAKING ROLLED STAY-BOLTS.

1,123,460.

Specification of Letters Patent.

Patented Jan. 5, 1915.

Application filed May 25, 1914. Serial No. 840,804.

To all whom it may concern:

Be it known that I, HENRY K. ADAMS, a citizen of the United States, residing at Nashville, in the county of Davidson and State of Tennessee, have invented certain new and useful Improvements in Apparatus for Making Rolled Stay-Bolts; and I do hereby declare the following to be a full, clear, and exact description of the invention, such as will enable others skilled in the art to which it appertains to make and use the same.

This invention relates to a machine for making rolled stay bolts, and has for its object to provide a means which will be comparatively inexpensive to construct and will be more certain and efficient in action than those heretofore proposed.

The invention consists in the novel combinations of parts, and details of construction constituting my machine, all as will be more fully hereinafter disclosed and particularly pointed out in the claims.

Referring to the accompanying drawings forming a part of this specification in which like numerals designate like parts in all the views—Figure 1 is a diagrammatic plan view of a machine made in accordance with my invention; Fig. 2 is an end elevational view of the parts shown in Fig. 1; Fig. 3 is a side elevational view of the parts shown in Fig. 2; Fig. 4 is a diagrammatic cross sectional view partly broken away of the rolls and certain coacting parts; Fig. 5 is a view of a stay bolt partially completed, after passing through my machine.

1 indicates any suitable power pulley mounted on the shaft 2 carrying the pinion 3 and meshing with the gear 4 provided with the integral clutch member 5 loose on the shaft 6 to which is rigidly attached the driving gear 7 meshing with the gear 8 rigid with the shaft 9 on which is mounted the upper roll 10. The lower roll 11 is rigid with the shaft 6, on which is also the clutch member 12 provided with the cam groove 13 and the controlling groove 14 in which enters the pin 15 carried by the lever 16 pivoted as at 17 to the bracket or frame 18, and carrying at its upper end 19 the pivot 20 engaging the plunger 21 controlled by the spring 22.

24 represents a foot treadle connected by the links 25 to the levers 26 pivoted at 27 to a lug or other portion of the framework, and connected as by the rod 28 as shown.

The said rod or bar 28 is joined as at 29 by the connecting member 30 which extends to the member 31 to which is connected the rod 32 pivoted as at 33 to the hand lever 34 which in turn is pivoted as at 35 to the frame or bracket 18. The extending end 36 of the lever 34 engages the plunger 37 controlled by the spring 38 the lower end 39 of which is adapted to enter the cam groove 13 on the clutch member 12 as will be readily understood. Each of the rolls 10 and 11 are provided with the smaller grooves 40 extending substantially one half way around the rolls or through an angle of say 180°, and each of the said rolls is further provided with the larger grooves 41 likewise extending substantially half way around each roll or through an angle of 180°, but of course the angular distance through which these respective grooves extend may be varied at will to suit the special work to be turned out.

As best illustrated in Fig. 4 a gage bar 50 resting upon a support 51 and controlled by a spring 52 is pivoted as at 53 to a short lever 54 pivoted on the rod 55 and having an end 56 adapted to enter the cam groove 60 with which the lower roll is provided as will be disclosed later. Further each of the large 85 semicircular grooves 41 in each roll 10 and 11 is joined at each end to its corresponding smaller groove 40 by an inclined surface 57 as will be clear from Figs. 1 and 4 of the drawings. These inclined surfaces 57 90 on the contiguous rolls are of such a shape as to form a beveled connection 58 between the head and the body of the finished bolt as will be clear from Fig. 5.

The operation of my invention will be 95 clear from the foregoing, but may be briefly summarized as follows: Power being imparted to the pulley 1 causes the shaft 2 to revolve and with it the pinion 3 and gear 4. If the clutch member 12 which is slideable on the shaft 6 is in engagement with the clutch member 5 which is loose on the shaft 6 and which is also rigid with the gear 4 power will be transmitted from the clutch member 5 to the clutch member 12, thence to the 100 shaft 6, the gear 7, gear 8, shaft 9, and roll 10. The roll 11 being fixed on the shaft 6 will also revolve and in a direction opposite to that of roll 10 as indicated by the arrows in Fig. 4. Bolt blanks 65 cut in suitable 110 lengths from rod like material and of a diameter substantially of the size of the fin-

ished bolt head may now be presented to the rolls as indicated in dotted lines in Fig. 4. The dimensions of the grooves 40 are such as to prevent the said blanks 65 from passing therethrough, while the dimensions of the grooves 41 are such as to permit the end of said blanks 65 to pass. Accordingly the operator presents said blanks 65 and when the matching grooves 41 come opposite the 10 end of said blank 65 the same passes between the rolls until it strikes the gage rod 50, whereupon the operator does not push the blank 65 any farther. The rolls 10 and 11 now continue to turn in the direction of 15 the arrows until the smaller matching grooves 40 begin to bite onto the blank 65. When this happens, the inclined surfaces 57 on the rolls 10 and 11 form at a predetermined distance from the end the beveled 20 surface 58 shown on the left hand end of the partly finished bolt illustrated in Fig. 5, and, the formation of the body portion 67 of the said bolt begins. As the smaller matching grooves 40 continue to pull the bolt 25 blank 65 through the rolls the extreme end 68 of said blank pushes the gage 50 off of its support 51 against the tension of the spring 52 and the said gage falls down from its full line position shown in Fig. 4 to its 30 dotted line position. In the meantime the bolt blank 65 continues to be forced through the rolls until the ends of the smaller grooves 40 are reached whereupon other inclined surfaces 57 on the rolls 10 and 11 35 form the beveled surface 58 shown on the right hand end of the partly finished bolt illustrated in Fig. 5. When the ends of the grooves 40 have been thus reached the other end of the enlarged grooves 41 will match 40 each other whereupon the enlarged right hand end of the partly finished bolt shown in Fig. 5 will pass through the rolls, and the said partly finished bolt will be ready to be 45 acted upon by any suitable machine for finishing off the heads. In the meantime, as the guide 50 falls from its support 51 the lever 54 turns on its pivot 55, and its other end 56 enters the groove 60 in the roll 11. As the said roll 11 continues to turn, the 50 cam groove 60 turns with said roll and forces down the end 56 of the lever 54 from its dotted line to its full line position shown in Fig. 4, and thereupon restores the gage bar 50 to its full line position illustrated in 55 Fig. 4, and thereby causes it to be ready for the reception of another bolt blank. It will thus be seen that the operator may rapidly and readily present blanks to the rolls, push them through as rapidly as he can until he 60 touches the gage bar 50 whereupon the machine takes hold of the blanks and completes the partly finished bolt at once, thus imparting to the finished bolt a rolled body portion 67 which of course is much stronger 65 and more desirable than a turned body.

When it is desired to start the machine it is only necessary to push down on the foot treadle 24 or to pull down on the hand lever 34, whereupon the extreme end 39 of the plunger 37 will be taken out of the cam groove 70 associated with the member 12 and the spring 22 will, through the levers 19 and 16 force the clutch member 12 into engagement with the clutch member 5 and thereby transmit power from the gear 4 and pulley 1 to the 75 rolls. The machine will now make one revolution and the spring 39 will of itself force the end 39 into the cam groove 13 and the rotation of the clutch member 12 will cause said cam groove to disengage the 80 clutch and the machine will stop. The cam groove 60 on the roll 11 is made of such dimensions as to comply with the requirements of the work to be turned out, and the same is true of the roll grooves 40 and 41. 85 The parts are so dimensioned that the grooves 41 always match when the machine stops, so the ends of blanks 65 may be readily passed through said grooves just as the operator starts the machine, and the 90 partly finished bolt may as readily be withdrawn after the machine stops. It will be thus seen that my machine not only turns out partly finished bolts by presenting blanks to and withdrawing them from the 95 grooves 41 as disclosed, but, I also provide a method by which finished bolts are given a rolled reduced body portion 67 and enlarged ends which are unacted upon by my machine, suitable for receiving any desired 100 shapes.

It is obvious that those skilled in the art may vary the details of construction, as well as the arrangement of parts without departing from the spirit of my invention and 105 therefore I do not wish to be limited to the above disclosure except as may be required by the claims.

What I claim is:

1. In a machine for rolling stay bolts the 110 combination of a pair of rolls having matching grooves of the size of the body portion of the finished bolt extending partially around their circumferences and matching grooves of a larger size joined to said first 115 mentioned grooves by inclined surfaces; a gage bar rest; a gage bar supported by said rest, associated with said grooves and adapted to be struck and displaced from said rest by a bolt blank while being subjected to the 120 action of said rolls; and means associated with said gage bar for restoring it to its normal position after having been displaced, substantially as described.

2. In a machine for rolling stay bolts the 125 combination of a pair of rolls provided with matching grooves to form the body of the bolt, and with enlarged matching grooves permitting the end of a bolt blank to pass; said first mentioned grooves joined to said last 130

mentioned grooves by surfaces adapted to shape the joint between the head and body of the finished bolt, and one of said rolls provided with a cam groove; and a gage bar 5 associated with said rolls and provided with means coacting with said cam groove, substantially as described.

3. In a machine for making stay bolts the combination of a pair of rolls having matching grooves of different dimensions; a gage bar adapted to operate in connection with said grooves; a rest on which said bar is supported; a lever adapted to operate said bar; and a cam adapted to operate said lever, substantially as described.

4. In a machine for making stay bolts the combination of a pair of rolls each provided with grooves of different sizes, the grooves on one roll matching with the grooves on the 10 other roll; a cam carried by one of said rolls; a lever adapted to be operated by said

cam; and a gage means adapted to operate said lever, substantially as described.

5. In a machine for making stay bolts the combination of a pair of grooved rolls 25 geared to each other one of which is provided with a cam; a shaft on which said last named roll is fixed; a gage bar associated with said rolls and controlled by said cam; a power pulley; a clutch member connected to said pulley loose on said shaft; a second clutch member slidable on said shaft; connections normally tending to cause said clutch members to engage; and means for causing said members to automatically dis- 30 engage, substantially as described.

In testimony whereof I affix my signature, in presence of two witnesses.

HENRY K. ADAMS.
